BARBER-COLMAN COMPANY, OF ROCKFORD, ILLINOIS.

TEXTILE-MACHINE.

1,183,276.

Specification of Letters Patent. Patented May 16, 1916.

Application filed February 24, 1910. Serial No. 545,599.

To all whom it may concern:

Be it known that I, HOWARD D. COLMAN, a citizen of the United States, residing at Rockford, in the county of Winnebago and 5 State of Illinois, have invented certain new and useful Improvements in Textile-Machines, of which the following is a specification.

In spinning fibers into yarn, the yarn is 10 wound upon bobbins or the like, each bobbin containing a single thread. To produce a warp it is usual to rewind the yarn from the bobbins onto spools or cheese-tubes, each spool or tube holding a single thread of a 15 length equivalent to the quantity of yarn upon a plurality of bobbins. A sufficient number of spools or cheeses are then rewound upon a section beam. It has also been proposed to rewind yarn upon a section beam 20 directly from the bobbins.

This invention relates to winders having means for automatically uniting the ends of the threads on bobbins to the ends of the threads on the spools, cheeses, section beam 25 or other yarn mass produced by the winder.

In application Serial No. 628,474 is shown a winder having means for automatically uniting the end of the thread on a cheese. When the thread being wound exhausts, the 30 loose end connected to the cheese becomes wound on the periphery of the cheese and is subsequently found by a traveling mechanism and tied to the end of the thread on a reserve bobbin.

35 The present invention has special, although not exclusive reference to machines for winding yarn from bobbins to spools, that is to say, to containers having flanges or heads at opposite ends to retain the yarn 40 mass on the container. In such machines the yarn is traversed or guided relatively slowly while the spool is being rotated, so that the yarn is wound approximately circularly upon the spool, as distinguished 45 from the spiral winding used in the production of cheeses. As it is very difficult mechanically to find the free end of the thread upon the periphery of a spool, it is an object of this invention to provide such 50 an organization of parts that the rotation of the spool shall be arrested before the exhausted thread is completely wound upon the spool, the loose end being caught and

held in position for operation thereon by a traveling yarn-uniting mechanism.

Other objects of the invention will be apparent from the following description of the present embodiment.

In the accompanying drawings, Figure 1 is a fragmental top plan view of a spooler 60 embodying the features of my invention. Fig. 2 is a transverse vertical section through the machine taken in the plane of dotted line 2—2 of Fig. 1. Fig. 2^a is a detail of the means for supporting a certain shaft 65 of the machine. Fig. 3 is a fragmental side elevation, with parts in section. Fig. 4 is a fragmental transverse vertical section. Fig. 5 is a detail view of one of the build bars. Fig. 6 is a detail view of one of the 70 tension-reducing rolls. Fig. 7 is a sectional detail view of the means for slidably supporting the build rail on dotted line 7—7 of Fig. 2. Fig. 8 is a fragmental transverse sectional view. Fig. 9 is an elevation of a 75 pair of the bobbin holders. Fig. 10 is a top plan view of said pair of bobbin holders. Fig. 11 is a fragmental perspective view of a shield and of one of the reserve thread clamps. Fig. 12 is a front view of 80 one of the groups of thread-controlling devices. Fig. 13 is a side view of said group of devices, the view being taken in the plane of dotted line 13—13 of Fig. 12. Fig. 14 represents a detector fork and a hook for 85 controlling the movements of said fork. Fig. 15 is a section on line 15 15 of Fig. 13. Figs. 16 and 17 are side views representing different positions of the thread-controlling devices. Fig. 18 illustrates one of the 90 spool-supports and related devices. Fig. 19 is a sectional view of said parts, the view being taken in the plane of dotted line 19 19 of Fig. 22. Fig. 20 is a section on line 20 20 of Fig. 18. Fig. 21 is a fragmental 95 view of a means for preventing upward displacement of the spool spindle. Fig. 22 is a top plan view of the spool support and related parts. Figs. 23 and 24 are details of a guide for the build bar. Figs. 25 and 100 26 are, respectively, a front elevation partly in section and a top plan view of the spool support and related devices, showing a different form of brake from that illustrated in Figs. 19 and 22. In Figs. 25 and 26 the 105 brake is represented as in the release posi-

tion. Fig. 27 is a top plan view showing the brake applied. Fig. 28 illustrates a means for holding the spool out of contact with the spool-rotating means. Fig. 29 is a sectional view of bobbin boxes located along each side of the spooler. Fig. 30 is a top plan view of a traveling winder-tending mechanism. Fig. 30¹ is a top plan view of certain thread forks and adjacent parts. Fig. 31 is a front elevation of the winder-tending mechanism. Fig. 32 is a fragmental vertical sectional view illustrating the operation of placing threads in operative relation to the knot-tying mechanism. Fig. 33 is a perspective view of a certain thread hook. Fig. 34 shows a cam drum and two of the levers operated thereby. Fig. 35 is a perspective view of a cam for raising the build bar in certain circumstances. Fig. 36 is a perspective view of two cams for holding the spool out of contact with the spool-rotating means at certain times. Fig. 37 represents the means for actuating a certain elbow lever. Fig. 38 is a top plan view of the rack and pinion for traversing the winder-tending mechanism. Fig. 39 is a section through said rack and pinion. Fig. 40 illustrates the means for driving said pinion. Fig. 41 is a rear side view of the knot-tying mechanism and coöperating parts. Fig. 42 is a detail of a reserve-thread clamp carried by said elbow lever. Fig. 43 illustrates a means for preventing variations in the thread-receiving position of said clamp. Fig. 44 illustrates the manner in which the elbow lever takes a reserve thread and an exhausted thread. Fig. 45 shows a means for bringing said threads into operative relation with the knotter. Fig. 46 represents a clamp for said threads and the means for placing the threads in said clamp. Fig. 47 is another view of certain parts shown in Fig. 45. Fig. 48 illustrates a means for elevating a looper into position to be placed upon a thread. Fig. 49 is a view of two exhaust air tubes and a means for operating a shear and a valve located in said tubes. Fig. 50 is a sectional view of said tubes and the valve. Figs. 51, 52 and 53 illustrate said shear, Fig. 51 being a section on line 51—51 of Fig. 52, and Fig. 52 being a section on line 52—52 of Fig. 51.

The embodiment herein shown of my invention comprises a spooler, *i. e.*, a machine for winding yarn from bobbins onto spools, and a mechanism arranged to travel along the spooler and attach the ends of the yarn on bobbins to the ends of the yarn on the spools. The spooler consists of a framework providing two parallel "sides", each side being equipped with means for rotatably supporting bobbins and means for supporting and rotating spools. In the present embodiment, the length of the sides and the speed

of winding are so proportioned to the quantity of yarn usually wound upon bobbins and to the speed at which the winder-tending mechanism travels that shortly before said mechanism reaches a given bobbin, said bobbin will have been emptied or "exhausted". It will, therefore, be understood that the winder-tending mechanism ties the end of the yarn on a fresh bobbin to every spool as said mechanism advances.

As shown in Figs. 2 and 3, the framework of the spooler may comprise a number of transverse frames 1 rigidly united by suitable longitudinal members as the rods 2 and the two angle-irons 3. The spools are supported from the angle-irons 3, while the bobbins lie in bobbin holders that are clamped upon two longitudinally extending rods 4. The rods 4, in this instance, are supported by arms 5 fixed to and rising from bars 6 that are rigidly attached to laterally extending arms 7 on the frames 1.

The bobbin holders may be of any suitable construction, but preferably partake of the form illustrated in Figs. 8, 9 and 10. As therein shown, the bobbin-holders are arranged in pairs, each pair accommodating a bobbin that is being unwound or has been exhausted and a reserve bobbin. In Fig. 8 *a* indicates an active bobbin and *b* a reserve bobbin. The bobbin-holder structure comprises a base 8 having thereon two pockets formed of loops 9 of cloth or other suitable material suspended from posts 10. The posts 10 are formed from an integral rod, the ends being attached to the base 8 and the middle portion 10^a being bent into loop form, as indicated in Fig. 9. A guide post 11 is fixed to the base in parallel relation to the posts 10 and arranged so as to form between itself and an adjacent post 10 a narrow opening for the passage of the yarn to the spool. The forward end of said post 11, is bent as at 12 and attached to one of the posts 10.

The build motion comprises, in this instance, two angle-iron rails 13 (Figs. 2 and 3) fixed to slides 14 which are slidably mounted upon vertical guides 15 (Fig. 7) attached to the frames 1. To a rock shaft 16 are fixed a suitable number of levers 17 which are connected by means of links 18 to the slides 14. The shaft 16 is rocked to raise and lower the build-rails 13 alternately by means of a cam 19 (Fig. 4) engaging a roller 20 on an arm 21 fixed on said shaft, and a weight 22 carried by an arm 22^a on the shaft 16, the weight holding the roller 20 against the cam 19. The cam 19 is mounted on a shaft 23 which carries at one end a spur gear wheel 24 meshing with an intermediate gear 25, the latter meshing with a pinion 26 fast on a shaft 27 (Figs. 2 and 3). On the shaft 27 is a worm wheel 28 meshing with a worm 29 on a vertical shaft 30. Power to

rotate the shaft 30 is derived from any suitable source, as a counter shaft (not shown) geared to a shaft 30' coupled at 30" to the shaft 30.

5 The spools are rotated by contact with a continuously moving endless belt 31 carried by a pulley 32 fixed on the shaft 30 and a similar pulley (not shown) at the other end of the spooler frame. Intermediate said pulleys the belt is confined between idlers 33 and 34 placed at suitable intervals at opposite sides of the belt. See Fig. 3.

For each spool there is a build bar 35 the lower end of which carries a pin 36 resting 15 on the build rail, the yarn being guided by the bent upper end of the bar 35. As the build rails 13 alternately rise and descend, the build bars direct the yarn to various heights upon the spools, thus causing the 20 yard to be wound evenly on the spools.

Referring now to Figs. 1, 2 and 2A, 37 are laterally extending arms attached to the frames 1 and supporting bars 38. Brackets 39 are fixed to the outer ends of the arms 37 25 and at intervals to the bars 38, and in these brackets are journaled shafts 40 which are rotated by any suitable means, as, for example, by means of grooved sheaves 41 and belts 42 running to any convenient source of 30 power, such as the countershaft before referred to. On each shaft 40 are fixed peripherally-grooved tension-reducing guide rolls 43 (Fig. 6) one for each spool, over which rolls the yarn runs in passing from 35 the bobbins to the spools. The peripheral speed of the rolls 43 is greater than the speed of winding, hence, while said rolls are incapable of positively feeding the yarn, they reduce the tension on the yarn between the 40 rolls and the spools, and thus insure that any breakage of the yarn due to weakness shall occur between the bobbins and the rolls.

44 (Figs. 12 and 13) are thread guides fixed upon the bars 38, the running threads 45 extending through said guides. Adjacent to each of the guides 44 is a thread clamp, the stationary member of which clamp, in this instance, consists of a round rod 45 (Fig. 12) lying in a rabbet formed in the bar 38 50 and attached to a bracket 46 screwed to said bar. The movable member 47 of the clamp is mounted upon a pivot 48. A coiled spring 49 (Fig. 13) bears against one side of the clamp member 47. The clamp member 47 is 55 adapted to hold between itself and the clamp member 45 a thread extending through the guide 44.

To an arm 50 of the bracket 46 is pivoted at 51 a lever 52 having thereon a finger 53 60 lying within an opening 54 in an arm 55 of the clamp member 47. Means to be later described tends at all times to swing said lever and close the thread clamp. The lever 52 is held against operation until the thread 65 passing through the adjacent guide 44 ex-

hausts, by means comprising a fork 56 fixed on a rock shaft 57 supported by the bracket arm 50, said fork consisting of a short tine 58 and a longer tine 59 between which the lower end of the lever 52 normally lies. 70 Fixed upon the shaft 57 is a detector fork 60 having bent tines 61 that are arranged to alternate with the tines of a stationary fork 62 mounted on an arm 63 that is fixed to the bracket 46. On its way to the spool, the 75 running thread extends from the active bobbin, over a guide pin 64, between the thread forks 60 and 62, and part way around the tension-reducing roll 43, the tension on the thread due to the drag of the bobbin preventing the detector fork 60 from swinging far enough to the right (Figs. 8 and 13) to permit the lower end of the lever 52 to slip past the short tine 58 of the fork 56. To prevent interference between the active 80 thread and the reserve thread, said threads are caused to pass at opposite sides of a finger 65 fixed to the pin 64. 65 are stops for limiting the swinging movement of the detector fork 60. 90

Shield sections 66 are fixed to the bar 38, a slot 67 (Figs. 1 and 11) being provided between every two adjacent sections and over each roll 43, for the entrance of the threads, as will appear more fully herein- 95 after.

For the free end of the yarn on each reserve bobbin there is provided a spring clamp 68 attached to the bar 38. A projection 68A (Fig. 12) prevents the thread from being 100 inserted too far back into the clamp, and insures that the thread shall have a definite operative position with relation to the device hereinafter described for taking the thread out of the clamp. 105

Between the tension-reducing roll 43 and the thread-clamp 45-47 the yarn passes around an idler roller 69 (Fig. 12) whereby a reserve-supply loop is formed in the thread to give sufficient length between the bobbin-holder and the spool so that the spool may be stopped before the end of the thread, when exhausted, has passed too far to be operated upon by the winder-tending mechanism. Said roller is mounted upon a slide 110 76 arranged for vertical movement upon a guide bar 71, loops or straps 72 (Fig. 17) on said slide serving to guide the latter in its movements along the guide bar. The idler roller 69 is inclosed within a housing 73 115 having a slot 74 in its walls to permit the thread to contact the roller, said slot having a flaring entrance portion 75. Upon the upper end of the slide 70 is a deflector 76 the purpose of which will appear hereinafter. 120 Normally the slide 70 rests upon the rail 6, as shown in Fig. 8. The device 69-70 will be hereafter termed the looper. 125

Secured to the angle-irons 3 are brackets 77 (Figs. 18 and 19) having aligned bearings 130

78 79 thereon. 80 is a shaft the upper portion of which is supported in the bearing 78. Upon the lower part of the shaft is loosely mounted a sleeve 81 having thereon a ratchet 5 disk 82.

The spool-spindle is carried by a frame 83 comprising the vertical sleeve 84 and the arms 85 86, said arms being loosely mounted on the upper end of the shaft 80 and the 10 sleeve 81, respectively. Fixed to the shaft 80 is a finger 87 carrying a pin 88. A coiled spring 89 surrounds the shaft 80 and the sleeve 81 between the bearings 78 79 and bears at its ends against the pin 88 and a 15 pin 90 set in the ratchet disk 82. The tension of the spring may be adjusted by rotating the disk 82, the disk being held in the desired position by means of a pawl 91 which is mounted on the arm 86. On the 20 upper end of the shaft 80 is fixed a crank arm 92. A link 93 is attached at one end to said crank arm and at its other end to a bracket 94 (Fig. 15), which bracket is slideable longitudinally of a slotted guide bar 95 25 fixed to the bracket 46. To the lower end of the bracket 94 is attached a link 96 that is connected to the lever 52 at 97. When the fork 56 holds the lever 52 from movement, the shaft 80 cannot rotate, hence the pin 88 30 forms a stationary abutment for the spring 89, which latter tends to swing the frame 83 in the direction to throw the spool against the constantly moving belt 31.

The spool-spindle 98 is rotatably mounted 35 in the sleeve portion 84 of the frame 83, the pointed lower end of the spindle resting upon a hardened metal screw-plug 99. Lubricating oil may be admitted to the interior of the sleeve 84 through ducts 100 101 (Fig. 40 21). 102 is a cap for closing the inlet end of the duct 101, said cap being fixed to an arm 103 which is pivoted at 104.

The spool rests upon a disk 105 fixed to the spindle 98, said disk having studs 106 45 thereon to fit into recesses in the lower end of the spool and thus prevent rotation of the spool with relation to the disk 105. Said disk has a peripheral flange 107 arranged to be engaged by a suitable brake device, as, 50 for example, a shoe 108 (Figs. 19 and 22) attached to a stem 109 which is pivotally connected with the crank arm 92 eccentrically to the shaft 80. The brake shoe is slideable between lugs 110 (Fig. 22). When the 55 detector fork 60 permits the shaft 80 to move, the spring 89 turns said shaft and presses the brake shoe 108 against the flange 107, thereby stopping the rotation of the spool. Both ends of the spring are now 60 bearing against the frame 83, consequently said spring exerts no tendency to swing the frame. Immediately upon the application of the brake, the momentum of the spool is absorbed by the pivoted frame 83, and said 65 frame immediately swings away from the

belt 31. The momentum of the spring 89, the arm 92 and the parts connected to said arm also play a small part in causing the swinging movement of the spool frame 83. To hold the spool in withdrawn position 70 collars 111 and 112 are fixed to the bearing 79 and the arm 86, respectively, said collars having upon their opposing faces low teeth which are brought into mesh, as shown in Fig. 28, when the spool leaves the belt, thereby releasably locking the spool out of contact with the belt. The teeth on the collars 111 and 112 permit of a little play between them.

In Figs. 25, 26 and 27 I have shown a band 80 brake which may be used in lieu of the brake shoe 108. One end of the brake band 113 is attached to the arm 85 and the other end to the crank arm 92.

To counteract any tendency of the disk 85 105 to rise during its rapid rotation, a hook 103^a (Fig. 21) is provided upon the arm 103, said hook overlying an inturned flange 107^a on the flange 107.

During the resetting of the detector mechanism by the winder-tending mechanism hereinbefore alluded to, the latter holds the spool out of contact with the belt 31 by means of a cam acting upon an arm 114 90 fixed to the frame 83.

The build bars 35 are guided in their vertical movements by means of guides 115 116, the guides 115 being rigidly fixed to the brackets 77. See Figs. 18, 22 and 23. It is desirable to retain each build bar in its most elevated position during the operation of 100 tying a reserve bobbin to the yarn on the spool, to attain which end I provide in the present embodiment the following described means.

The guide 116 is pivoted at 117 and 105 is normally held in such position that the build bar can pass freely through the guide, by the finger 87, the guide having a stud 118 thereon which rests on the finger. When the finger is withdrawn by the brake-applying movement of the shaft 80, the guide 116 drops into the position indicated in Fig. 23 whereupon the downward movement of the build bar 35 is prevented by reason of binding of said bar in the guide. It will be 110 seen that should the finger 87 be withdrawn when the build bar is not in its most elevated position, the guide 116 does not prevent the build bar from rising, but engages the bar as soon as the latter starts to descend from its highest position. When the finger 87 is returned to its normal position, the inclined surface 119 on said finger engages the pin 118 and raises the guide 116 115 into the position represented in Figs. 18 and 24. 120 is a stop pin to limit the upward movement of the guide, and thus prevent the build bar from frictionally raising said guide during the normal operation of the build bar.

As will be understood from an inspection of Figs. 2 and 8, in each side of the spooler there is a space 121 between the row of bobbin-holders and the row of spool-supporting devices. The winder-tending mechanism before referred to travels through this space, moving continuously in an endless circuit. In the form illustrated in the present drawings, said mechanism comprises a carriage or framework indicated generally in Fig. 31 by the numeral 122. Said carriage in this instance is provided with rollers 123 which travel upon an endless track 124 supported in a suitable way, as by means of standards 125 (Fig. 2). The track 124 has straight sides and curved ends, the straight portions of the track extending parallel with the rows of spool-spindles and bobbin-holders. Two pairs of rollers 126 engaging opposite sides of the rail or track 124 prevent lateral displacement of the machine. On the upper end of the carriage 122 is fixed a lug 127 (Figs. 30 and 40) which fits over an endless guide rail 128 arranged parallel with the track 124 and supported upon the spooler frame in any suitable manner.

The winder-tending mechanism is caused to travel along the spooler and perform its function by an electric motor 129 (Fig. 31) mounted in the carriage 122. The motor is connected in an electric circuit in any suitable way, for instance, by means of two contact springs 130 attached to and insulated from the carriage 122 and contacting two endless conductors 131 arranged at opposite sides of and insulated from the rail 124 and from each other. Said conductors are included in an electric circuit (not herein indicated). The contact springs 130 (only one of which is shown in the drawings) are electrically connected to the motor in any approved way.

On the armature shaft is a pulley 132 (Fig. 31) carrying a belt 133 which passes around a pulley 134 fixed on a shaft 135. A worm 136 (Fig. 37) fast on the shaft 135 meshes with a worm wheel 137 fixed on a shaft 138. The last mentioned shaft carries a spiral gear wheel 139 that meshes with a similar gear wheel 140 (Fig. 40) fixed to the lower end of a shaft 141. On the upper end of the shaft 141 is a pinion 142 meshing with an endless rack 143 extending parallel with the guide rail 128. The pinion 142 is connected to the shaft to rotate therewith by means herein shown as a spring plunger 144 (Fig. 39) slidable in a collar 145 fixed to the shaft, the lower end of said plunger being adapted to enter a socket 146 in the pinion. Fixed to the head of the plunger is a pin 147 which lies in an opening 148 in the collar 145 when the plunger engages the pinion. When the plunger 65 is withdrawn from engagement with the

pinion and given a partial rotation the pin 147 stands on the top of the collar 145 or in a shallow recess 149 in the collar and thus holds the plunger in inoperative position. When the pinion is disconnected from the shaft the winder-tending mechanism may be moved by hand, forward or back, in case an adjustment of the position of said machine should be desirable. The lug 127 holds the pinion in mesh with the 75 rack 143.

The various mechanisms that constitute the yarn-uniting mechanism are driven from the shaft 138. Of said mechanisms the knot-tying mechanism may be first described. Referring to Fig. 32: The knotter frame 150 is rigidly secured to the carriage frame 122 and supports a rotatory shaft 151 carrying at its lower end a pinion 152 that meshes with a gear wheel 153 on the 85 upper end of a shaft 154. On the lower end of the shaft 154 is a bevel gear wheel 155 meshing with a similar gear wheel 156 on the main shaft 138.

The rotatory knotter bill 157 is substantially similar in construction to that shown in Patent No. 959,592, dated May 31, 1910. Its shaft is rotatably supported in suitable bearings and is driven by means of a gear connection with the shaft 151, as in said patent. The knot formed by the bill is stripped from the bill and tightened by a rotatory stripper hook 158 driven from the shaft 151 substantially as shown in said patent. Fixed to the upper end of the knotter frame 150 are two plates 159 160 spaced apart as indicated in Fig. 41 and forming the stationary portions of a thread clamp. Said plates lie just above the rotatory stripper hook 158. A plate 161 is fixed to the knotter frame just below the stripper hook, the threads acted upon by the tying bill and the stripper hook extending across the edge of said plate. Fixed to the knotter frame and lying in a horizontal plane just above the clamp plates 159 160 is a plate 162, (Figs. 30² and 41) across the edge of which plate the threads are drawn by means to be hereinafter described. On one end of said plate is an up-turned guard lug 163. 110

Below the tying bill 157 is a suction air tube 164, the rear wall of said tube being represented in Fig. 41 as partially broken away. The upper wall of the air tube has formed therein a throatway 165, a plate 166 having a similar throatway being fixed to said upper wall. See Fig. 46. Threads inserted into said throatway are yieldingly clamped by a spring clamping arm 167 which bears against the plate 166 and is arranged to be swung into and out of position to clamp the threads by a cam 168 and a tension spring 169 operating upon an arm 170 fixed to the clamping arm 167. The cam 168 is rigidly mounted upon the shaft 151. 120

125
130

The exhausted thread and the reserve thread are brought together and placed in operative relation with the knotter by means herein shown as an elbow lever 171 consisting of the arms 172 173 (Figs. 32 and 44). Said lever is fixed upon a shaft 174 (Fig. 31) which in this instance is rocked to swing the lever by means of the gearing illustrated in Fig. 37. A bell-crank lever 175 is pivoted at 176, one arm of said lever carrying a gear segment 177 meshing with a pinion 178 on the shaft 174, and the other arm carrying a roller mounted in a cam groove 179 formed in the worm wheel 137.

On the outer end of the arm 173 is a device that serves as a clamp for the reserve thread and as a hook to engage the exhausted thread. Said device in the present instance is constructed and operated as follows: On the free end of the arm 173 is fixed a finger 180 (Figs. 32 and 41) extending at an angle with said arm. To said finger are fixed two plates 181 182 spaced apart and forming the relatively stationary part of the reserve-thread clamp. Said plates extend parallel with the arm 173. A slide 183 (Fig. 44) of approximately the same length as the arm 173 has thereon a dove-tail guide 184 (Fig. 41) that is mounted in a longitudinal groove in the arm 173, whereby said slide is supported for sliding movement longitudinally of said arm. On one end of the slide 183 is fixed a finger 185, and to the finger is rigidly attached a plate 186 (Figs. 41 and 42) adapted to enter the space between the plates 181 182 and constituting the movable member of the reserve-thread clamp. As shown in Figs. 31 and 41 the operative portions of the clamp plates 181 182 are located at the forward side of the elbow lever 171. On one side of the plate 182 and at the outer end thereof is a lug 187.

The slide 183 is moved to open and close the clamp by means herein shown as comprising a lever 188 (Fig. 44) pivoted between its ends at 189 on the arm 172. One end of the lever 188 has a gear connection 190 with one end of the slide 183, while the other end of the lever is forked to receive a pin 191 set in an arm 192 (Fig. 31) fixed to one end of a rock shaft 193 (Fig. 34). The other end of said shaft bears an arm 194 (Figs. 31 and 34) carrying a roller that lies in a cam groove 195 formed in a cam drum 196 fixed on the main shaft 138.

Assuming the elbow lever to have been swung into the position shown in Fig. 44, the clamp being open, the progressing movement of the winder-tending mechanism carries the open clamp onto the reserve thread held in the spring clamp 68. The clamp on the elbow lever thereupon closes and the elbow lever swings in the direction indicated by the arrow in Fig. 44, pulling

the reserve thread out of the clamp 68 and drawing the thread up and back, said thread passing through the slot 67 onto the roll 43. Continuing in its movement the elbow lever brings the reserve-thread clamp 181 182 186 against the portion of the exhausted thread extending between the clamp 45 47 and the uplifted build bar, and draws a bight of said exhausted thread, together with the reserve thread, across the edge of the guide 162 and into the position shown in Fig. 32, the lug 187 guarding against accidental escape of the exhausted thread from the elbow lever. When the elbow lever reaches the position represented in Fig. 32 the clamp 181 182 186 opens. The threads having been removed from the clamp 181 182 186 by means to be later described, said clamp closes so as to restore the point 191 to the axis of rotation of the elbow lever. Upon completion of the ensuing upward swinging movement of said lever, the clamp again opens to receive another reserve thread.

In order to obviate the effect of possible back-lash in the gearing 177 178, (Fig. 37) upon the thread-receiving position of the clamp 181 182 186, I provide a spring plunger 171^a (Fig. 43) carried by the elbow lever 171 in position to bear against the bar 38 when said lever reaches the position shown in Fig. 44.

It will be seen from an inspection of Fig. 32 that by reason of the loop or bight formed in the exhausted thread by the elbow lever, there are three strands extending downwardly behind the guide 162. To remove the extra strand, to wit, the loose end of the exhausted thread, in order to prevent its being tied into the knot, I provide the following described mechanism.

Referring to Figs. 31 and 32; 197 is a peripherally grooved drum fixed upon a shaft 198 carried by a bearing 199. Said drum is located directly below the clamp 181 182 186 when said clamp is in the position shown in Fig. 32. Fixed to the side of the drum is an arm 200 having thereon a hook 201 arranged to engage the extra strand when the drum and hook are revolved, and draw said extra strand away from the knotter and in doing so wrap said strand part way around the drum. While the hook 201 is thus withdrawing the waste or extra strand, the lug 187 prevents the exhausted thread from slipping off the plate 182.

The drum and the hook are revolved by means herein shown as comprising a bell crank lever 202 pivoted at 203, one arm of said bell crank lever carrying a gear segment 204 meshing with a pinion 205 fixed on the shaft 198, and the other arm carrying a roller engaging in a cam groove 206 (Fig. 31) in the cam drum 196.

It is desirable that the loose ends of ex-

hausted threads be of uniform length, since the extent of movement of the hook 201 is invariable. I therefore provide a mechanism for trimming the loose ends of the exhausted threads and disposing of the trimmed-off portions. A suction air tube 207 (Figs. 30, 31 and 49) is arranged in the carriage 122 with its inlet end in the vertical plane of the exhausted ends hanging 5 from the clamps 45 47, so that as the winder-tending mechanism progresses said air tube takes the exhausted threads singly. When a thread exhausts, the brake stops the spool as hereinbefore described, leaving the exhausted end hanging in the path of the suction tube 207. In the suction tube 207 is a shear consisting of the fixed blade 208 and the movable blade 209 (see Figs. 51, 52 and 53). The shear is actuated at proper times 10 to trim off the end of an exhausted thread received in the air tube 207, by means comprising a shaft 210 to which the blade 209 is fixed. On one end of said shaft is fixed an arm 211 which is connected by a link 212 to an arm 213. Said arm 213 is rigidly mounted on a shaft 214 carrying an arm 215 that has a roller engaging in a cam groove 216 in the cam drum 196. The trimmed-off ends are carried away by the current in the 15 air tube 207.

The exhaust air tube 164 merges with the tube 207 in the common conduit 217 (Fig. 31) which is connected with an exhaust fan 218 driven by the motor 129. The fan discharges through a tube 219 into a centrifugal separator 220 of any approved construction. In order to open the tubes 164 and 207 alternately, as needed, I provide a valve member 221 (Fig. 50) located at the junction of the 20 branches 164 207 and fixed on a shaft 222. Attached to said shaft is an arm 223, (Fig. 49) which is connected by a link 224 with an arm 225 on the shaft 214.

The threads pulled down behind the guide 25 162 by the elbow lever 171 are advanced into operative relation to the knotter by means to be now described. A slide 236 (Figs. 45 and 47) is mounted on a guide 227 and is reciprocated toward and away from the knotter 20 by a lever 228 pivoted at 229, the upper end of said lever carrying a roller that lies in an elongated opening 230 in the slide. Between its ends the lever 228 bears a roller that engages a grooved cam 231 on the main shaft 25 138. The slide 236 carries a fork 232 lying in a plane above the knotter, and two forks 233 234 situated in a plane below the knotter (see Fig. 41), said forks engaging the reserve thread and the exhausted thread and laying them across the tying bill 157 as the slide 236 advances. The forks 233 234 insert the threads into the suction tube 164 and into the throatway 165, where they are yieldingly held by the spring clamping arm 167. At the 30 same time a fork 235 on the slide 236 inserts the threads between the clamp plates 159 160 where they are tightly clamped, the slack required by the bill 157 in forming the loops of the knot being supplied from the strands held by the clamp arm 167. After the loops 35 of the knot have been formed and the waste ends clipped off by the tying bill the stripper hook 158 presses the strands into the space between the clamp 159 160 235 and the plate 161, thereby pulling the loops off the bill 157, 40 tightening said loops and pulling the ends out of the bill. The waste ends, including the strand pulled down by the hook 201, are drawn into the suction tube 164 by the exhaust air current therein.

A stationary guard 236 (Fig. 41) is provided just above the path of the fork 232 and near the rear end of said path so that should the united threads accidentally cling to said fork they will be stripped therefrom as the 45 fork passes under said guard.

While some of the operations hereinbefore described are occurring, the slide 70 is being elevated to place the roller 69 above the reserve thread and in position to drop upon 50 said thread when the latter is united to the exhausted thread. Referring to Figs. 17, 30, 31 and 48: An endless chain 237 is supported upon the sprocket wheels 238 239 in a plane inclined upwardly from front to rear. On 55 said chain are three equidistant projections 240, one of which is hidden from view by the other parts in the drawings. These projections are so located and moved by the chain that as the winder-tending mechanism advances a projection will pass under the lug 241 of each slide 70 in succession. As the projection moves upward the slide is raised until the roller 69 is projected through the space 66^a (Fig. 11) between the shield sections 66, the inclined face or deflector 76 pushing the thread aside to permit the roller 69 to rise above the thread. As soon as the roller housing 78 passes the thread, the latter 60 springs under the housing and into a position directly below the throatway 75. When the projection 240 reaches the position occupied by the upper projection in Fig. 31, the continuing movement of the chain carries the projection laterally away from the lug 241 and leaves said lug on the surface 242 of a plate-like support 243. The onward movement of the winder-tending mechanism moves the surface 242 out from under the lug 241, whereupon the slide 70 drops until 65 said lug rests on the surface 244. The descent of the slide is somewhat retarded or checked by the inclined surfaces 245 246. In its descent the roller 69 on the slide 70 carries a loop of the thread with it, thus taking up 70 most of the slack formed when the completed knot is released by the knot-tying mechanism. When the surface 244 passes out from under the lug 241 the slide 70 drops into its 75 normal position as shown in Fig. 8, such de-

scent being checked by the action of the inclined surface 247 upon the lug 241.

The chain 237 is moved by means of a spiral gear 248 fixed on the main shaft 138 and meshing with a similar gear 249 on the shaft of the sprocket wheel 239.

When a thread exhausts, the detector fork 60 is thrown into the position indicated in Fig. 16 through the action of the spring 89. In order to restore the detector fork 60 into operative relation with the new active thread, the following described instrumentalities are provided.

Fixed in the framework of the winder-tending mechanism is a plate 250 (Fig. 30) having thereon cam surfaces 251 252 and a dwell 253. As the winder-tending mechanism advances, the cam surface 251 engages the bracket 94 and pushes it to the left (Fig. 16) into the position shown in Fig. 17, the lower end of the lever 52 striking the fork-arm 59 and swinging the detector fork 60 into the position indicated in Fig. 17. If the reserve thread should extend across the path of the detector fork, the inclined form of the tines 61 causes the thread to be pressed aside to the left (Fig. 14) as the detector fork swings into the position referred to.

A stop 254 is pivoted on the under side of the bar 38 in position to lie in the path of movement of the detector fork 60 when the latter is moving toward its operative position. An arm 255 on said stop carries a pin 256 arranged to be engaged by a cam 257 (Fig. 30) on the winder-tending mechanism for swinging said stop out of position to interfere with the movement of the detector fork, a spring 258 (Fig. 14) tending to swing the stop into operative position. Before the cam 251 moves the detector fork into the position shown in Fig. 17, the cam 257 withdraws the stop 254 from the path of movement of the fork, but after the fork has reached said position and the dwell 259 has passed the pin 256 the spring 258 moves the stop 254 into its normal position in contact with the end of the upper tine of the fork 62. Thereafter and until the knot has been tied, the dwell 253 holds the detector fork in the position shown in Fig. 17. When the cam 252 is reached the spring 89 is permitted to draw the detector fork rearwardly until said fork stops against the end of the stop 254, during which movement the detector fork engages the thread and moves it toward the running position. If the detector fork were supported by the thread and the thread broke while the winder-tending mechanism were behind the detector fork, it will be seen that said fork might swing into the path of the looper. Such possibility is obviated by supporting the detector fork upon the stop 254 until the winder-tending mechanism has passed the fork, when the cam 261 (Fig. 14) engages the pin 256 and,

withdrawing the stop 254, permits the detector fork to carry the thread against the stationary fork 62.

An elongated dwell 260 may be used to limit the action of the spring 89 on the detector 60, the bracket 94 sliding along said dwell, but the stop 254 is the preferred construction.

In order to permit of the swinging movements of the elbow lever 171 the dwell 260 is interrupted by an opening that is closed by a gate 262 hinged at 263. When said elbow lever swings upwardly it pushes the gate aside, the gate being closed when it is carried into contact with the bracket 94.

When the cam 251 pushes the bracket 94 from the position indicated in Fig. 16 to that represented in Fig. 17, the brake 108 or 113 is released. In order to hold the spool frame 83 stationary while the spring 89 is being tightened or reset by the cam 251 and to prevent the spring 89 from throwing the spool against the belt until the thread connection between the spool and the bobbin has been re-established, I provide upon the rear side of the winder-tending mechanism a cam 264 (Figs. 30 and 36) arranged to engage the end of the arm 114 during the travel of said mechanism before the brake is released through the action of the cam 251 upon the bracket 94. When the looper 69 70 takes up the slack in the united threads, the tension thus placed upon the threads tends to cause rotation of the spool, therefore just before the looper is released to downward movement the arm 114 is engaged by a cam 266 (Fig. 36) that is somewhat higher than the cam 264, said cam 266 moving the arm 114 to press the flange 107 (or the brake band encircling said flange) 105 against a brake device 265. Said brake device consists of a yielding finger fixed in this instance upon the rear side of the rack bar 143.

When the spool brake 108 or 113 is released by the cam 251, the movement of the finger 87 lifts the guide 116 into normal position, thereby releasing the build bar 35. To prevent the build rail 13 from moving the build bar while the exhausted thread is being operated upon at the knotter, I provide on the carriage 122 an inclined cam bar 267 (Figs. 31 and 35) adapted in the travel of the carriage to engage the lower end of the build bar and raise said bar to its uppermost position just prior to the time when the elbow lever 171 swings into contact with the thread lying across said build bar. The dwell 268 is at a slightly lower level than the top of the cam portion 267, allowing the build bar to drop and give up slack as the slide 226 moves forward.

At each side of the spooler may be placed a row of bins 269 (Fig. 29) to receive the empty bobbins removed from the bobbin-

holders by the operative, and a row of bins 270 to contain full bobbins. Preferably the bins 270 are removably supported upon the bins 269. Behind each bin 270 is a space 271 communicating with the bin 269 just below it. Each bin 270 has a rearwardly sloping upper wall 272 which leads to the space 271 so that empty bobbins laid by the operative upon said upper wall will roll into 10 and through the space 271 and be received in the bin 269.

In use, the operator keeps each pair of bobbin-holders supplied with a reserve bobbin, the end of the yarn on said bobbin 15 being placed in the adjacent clamp 68. Practically all exhausts are caused by the emptying of the bobbins, breakages of yarn being relatively infrequent. By the time the winder-tending mechanism reaches any 20 given spool, the bobbin generally will have been emptied and the spool will stand in the position indicated in Fig. 27, being in such position out of contact with the drive belt 31. The detector fork 60 will stand in 25 the position shown in Fig. 16. As the winder-tending mechanism advances, the cam 257 moves the stop 254 aside; the cam 251 moves the detector fork 60 into the position shown in Fig. 17; the shear 208 209 30 trims off the loose end of the exhausted thread, the trimmed-off end being drawn into the suction tube 207 and blown into the separator 220; the elbow lever 171 swings upwardly, catches the reserve thread 35 as shown in Fig. 44, and swings rearward and downward in the direction indicated by the arrows in Figs. 44 and 32, carrying a reserve thread and a bight of the exhausted thread down behind the plate 162, as shown 40 in Fig. 32; the hook 201 draws the free end of the exhausted thread downwardly and around the drum 197; the clamp 181 182 186 opens; the forks 232, 234 and 235 move the two strands forward into operative relation 45 with the knotter; the knotter unites said threads and cuts off the ends of the strands beyond the knot; and the suction air tube 164 removes the trimmed-off ends. The looper 69 70, having been raised by the chain 50 237, is now dropped onto the united threads, thereby drawing said threads away from the vicinity of the knotter and taking up the slack in said threads, and the cam 252 permits the spring 89 to swing the detector fork 55 lightly against the newly formed thread connection, said fork resting against the stop 254. As the rear end of the winder-tending mechanism passes the spool, the cam 261 withdraws the stop 254, thereby permitting 60 the fork 60 to rest wholly upon the thread. Just before the cam 266 permits the spring 89 to throw the spool into driving contact with the belt 31, the cam 247 permits the looper 69 70 to descend. As said looper 65 descends, it draws thread from the bobbin,

thus starting the rotation of the bobbin before the spool is set in rotation, and thereby gradually bringing the bobbin up to working speed.

When a spool becomes filled, the operator 70 replaces the filled spool with an empty spool when the bobbin exhausts, attaching one end of a piece of yarn to the spool and carrying the other end of said piece of yarn over the shield 66 and beneath a hook 273 (Figs. 12 75 and 13) located, in this instance, upon said shield. The operation of tying a reserve thread to the length of yarn extending from an empty spool is precisely the same as in the case of an exhaust, except, of course, 80 that said piece of yarn is not acted upon by the shear 208 209.

The foregoing detailed description of the present embodiment should not be understood as an undue limitation of the invention, for various changes may be made in the construction and arrangement of the various mechanisms, and certain features of the invention are applicable to other uses than that herein described. 85

In certain of the claims, I have, for the sake of brevity, used the term "a winding couple" to indicate two yarn masses, one of which is being unwound onto the other, without regard to the form or location of 95 such masses.

I claim as my invention:

1. A winder having, in combination, a mechanism for winding a thread; a knot-tying mechanism; and means for moving 100 said knot-tying mechanism in a circuit, a portion of which circuit extends beneath a portion of the thread being wound.

2. A winder having, in combination, a mechanism for winding a thread; a knot-tying mechanism; and means for moving 105 said knot-tying mechanism in a circuit, a portion of which circuit extends transversely of and beneath a portion of the thread being wound.

3. A winder having, in combination, a thread-uniting mechanism arranged to travel in a circuit; means for winding a thread, with the thread running transversely of and above the path of the uniting 115 mechanism; and means for moving the thread into operative relation to the uniting means.

4. A winder having, in combination, a supporting frame, a series of means on the frame, for supporting winding couples; means on the frame for supporting reserve and exhausted threads; and a traveling winder-tending mechanism comprising a knot-tying mechanism and a pivoted arm 120 adapted to engage a reserve thread and an exhausted thread and move them to the knot-tying mechanism. 125

5. The combination of an elongated supporting frame; an endless track in said 130

- frame, said track having opposite straight portions and curved ends connecting said straight portions; pairs of bobbin-holders supported along the outer side of the 5 straight track-portions; means for unwinding one of the bobbins in each pair of holders toward the inner side of the straight track-portions, whereby the running threads pass across said straight track-portions; and 10 a knot-tying mechanism arranged to travel upon said track.
6. A winder having, in combination, a series of spool-supports; a series of bobbin-supports; stationary means for supporting 15 reserve and exhausted threads; and a traveling thread-uniting mechanism adapted to unite a reserve thread to an exhausted thread.
7. A winder having, in combination, a series of spool-supports; a series of bobbin-supports; stationary means for supporting reserve and exhausted threads; and a traveling thread-uniting mechanism comprising a 20 knot-tying mechanism and a pivoted arm 25 adapted to engage a reserve thread and an exhausted thread and move them into position adjacent to the knot-tying mechanism.
8. A winder having, in combination, a row of spool-supports; a row of bobbin-supports; means for supporting reserve and exhausted threads, said exhausted threads extending across the space between said rows of devices; and a thread-uniting mechanism 30 arranged to travel through the space between said rows of devices and beneath the exhausted threads, said mechanism comprising a knot-tying mechanism and a swinging arm arranged to engage a reserve thread and an exhausted thread and move them into 35 position adjacent to the knot-tying mechanism.
9. A winder having, in combination, a spool-support; a bobbin-support; stationary means for supporting an exhausted thread; 40 means for supporting a reserve thread; a knot-tying mechanism; and a swinging arm arranged to engage said threads and move them into position adjacent to the knot-tying mechanism.
10. A winder having, in combination, a spool-support; a bobbin-support; means for supporting an exhausted thread; means for supporting a reserve thread; a knot-tying mechanism; a swinging arm carrying a 45 clamp adapted to receive and hold the reserve thread, said arm being arranged to swing said clamp against the exhausted thread and carry the end of the reserve thread and a bight of the exhausted thread 50 into position adjacent to the knot-tying mechanism; and means for withdrawing one strand of said bight.
11. A winder having, in combination, a container-support; a bobbin-support; means for supporting an exhausted thread; means
- for supporting a reserve thread; a knot-tying mechanism; means for moving one of said threads and a bight of the other thread into proximity to the knot-tying mechanism; and means for withdrawing one 70 strand of the bight.
12. A winder having, in combination, a container-support; a bobbin-support; means for supporting an exhausted thread; means for supporting a reserve thread; a knot-tying mechanism; means for moving one of said threads and a bight of the other thread into proximity to the knot-tying mechanism; a swinging hook adapted to engage said bight; and a drum over which said hook is arranged to pull one strand of said bight. 75
13. A winder having, in combination, a container-support; a bobbin-support; means for supporting an exhausted thread; means for supporting a reserve thread; a knot-tying mechanism; means for trimming off one end of one of said threads; means for moving a bight of the last mentioned thread and the end of the other thread into proximity to said knot-tying mechanism; and means for withdrawing one strand of said bight. 80
14. A winder having, in combination, a container support; a bobbin-support; means for supporting an exhausted thread; means for supporting a reserve thread; means for uniting said threads; a looper; and means for placing said looper on the united threads. 90
15. A winder having, in combination, a container-support; a bobbin-support; means for supporting an exhausted thread; means for supporting a reserve thread; means for uniting said threads; a looper; means for placing said looper in position to drop upon the united threads; and means for controlling gravitating movement of said looper. 100
16. A winder having, in combination, a container-support; a bobbin-support; means for supporting an exhausted thread; means for supporting a reserve thread; means for uniting said threads; a looper; means for placing said looper in position to drop upon the united threads; and cam means for controlling the gravitating movement of said looper and for dividing said gravitating movement into two stages, during one of which stages the looper takes up slack in the united threads, and during the other of which stages the looper starts the bobbin to rotating. 110
17. A winder having, in combination, container-rotating means; a bobbin-support; means for supporting an exhausted thread; means for supporting a reserve thread; means for uniting said threads; and means other than said container-rotating means for setting the bobbin in rotation. 120
18. A winder having, in combination, 130

- container-rotating means; a bobbin-support; means for supporting an exhausted thread; means for supporting a reserve thread; means for uniting said threads; means for preventing rotation of the container; and means for starting the bobbin to rotating before said preventing means permits the container to rotate.
19. A winder having, in combination, a pocket in which a bobbin may lie loosely; means for drawing yarn from the bobbin and thus setting the bobbin in rotation; and receiving-container-rotating means acting subsequently to the beginning of operation of said yarn-drawing means, to draw yarn from the bobbin and continue the rotation of the latter.
20. A winder having, in combination, container-rotating means; a bobbin-support; means for supporting an exhausted thread; means for supporting a reserve thread; traveling means for uniting said threads; means traveling with said uniting means for preventing rotation of the container; means for initiating rotation of the bobbin; and means traveling with said uniting means for controlling said rotation-initiating means.
21. A winder having, in combination, container-rotating means; a bobbin-support; means for supporting an exhausted thread; means for supporting a reserve thread; traveling means for uniting said threads; means traveling with said uniting means for preventing rotation of the container; means for initiating rotation of the bobbin; and means traveling with said uniting means for controlling said rotation-initiating means, said controlling means permitting actuation of said rotation-initiating means before said preventing means is moved out of operative relation to the container-rotating means.
22. A winder having, in combination, a container support; a bobbin support; a looper; means for raising said looper into position for placing it on a thread extending between a bobbin and a container on the respective supports; and a detector for detecting exhaustion of said thread before the end of the thread has reached the loop.
23. A winder having, in combination, a container-support; a bobbin-support; a looper; means for placing said looper in position to drop upon a thread extending between a bobbin and a container on the respective supports; and means for controlling the descent of said looper.
24. In a textile machine, in combination, means for supporting a thread; a looper supported for vertical movement; mechanism arranged for horizontal movement, said mechanism comprising an endless chain supported in an inclined plane and carrying means to engage the looper; and means for moving said chain in the travel of said mechanism for elevating said looper into position to drop upon the thread.
25. A winder having, in combination, means for supporting a plurality of winding couples; devices for guiding the running thread extending between the members of each couple; and means for trimming off the ends of exhausted threads while hanging from said guiding devices.
26. A winder having, in combination, a row of container-supports; thread-guiding means associated with each container-support for guiding the thread to the container; and means arranged to travel longitudinally of said row of container-supports for trimming the ends of exhausted threads to a uniform length while hanging from said thread-guiding means.
27. A winder having, in combination, a row of container supports; means for supporting the exhausted ends of the yarn on containers carried by said supports; and means arranged to travel longitudinally of said row of container-supports, said means comprising an exhaust air tube located in position to be brought into proximity to successive exhausted threads, and a thread sheer located in said tube.
28. A winder having, in combination, means for supporting exhausted threads; a row of clamps for reserve threads; and a thread-uniting mechanism arranged to travel longitudinally of said row of clamps, said mechanism comprising a knot-tying mechanism and a swinging arm carrying a clamp; means to actuate the clamp; and means for swinging said arm to place said clamp in position to take successive reserve threads and bring said threads into proximity to said knot-tying mechanism, said arm being adapted to place an exhausted thread in proximity to said knot-tying mechanism.
29. A winder having, in combination, a row of container supports; a row of clamps for the ends of exhausted threads of containers located on said supports, said rows being parallel; a knotter arranged to travel transversely of the exhausted threads; and means for moving the exhausted threads successively to the knotter.
30. A winder having, in combination, a row of container supports; a row of clamps for the ends of exhausted threads of containers located on said supports; said rows being parallel; a knotter arranged to travel between and below said rows; and means for moving the exhausted threads to the knotter.
31. A winder having, in combination, a row of container supports, a row of clamps for the ends of exhausted threads of containers located on said supports, said rows being parallel, a knotter arranged to travel longitudinally of said rows, a reserve thread holder adjacent to each of said clamps, and

means for moving a reserve thread and an exhausted thread to the knotter.

32. A winder having, in combination, a bobbin-support, winding-means, means for forming a reserve-supply loop in the thread between the bobbin and the winding means, and tension-reducing means operating upon the thread at a point between the bobbin and the loop-forming means, the tension-reducing means consisting of a roll having a greater peripheral speed than the speed of winding.

33. A winder having, in combination, means for supporting a winding container; means for supporting an active and a reserve thread supply therefor; a clamp acting to hold the active thread before its end can be wound on the container; and a thread uniter to unite the reserve and active 20 threads.

34. A winder having, in combination, a series of clamps to hold exhausted threads, and means to trim the free ends of said threads to a uniform length.

35. A winder having, in combination, a clamp to hold an exhausted thread, a knotter, an arm to move said thread into proximity to the knotter, and a shear acting in advance of the arm to trim the clamped end 30 to a uniform length.

36. A winder having, in combination, a series of clamps to hold exhausted threads, a knotter, a device for moving said threads successively into proximity to the knotter, 35 and thread-trimming means arranged to operate in advance of said device to trim the free ends of said threads to a uniform length.

37. A winder having, in combination, a knotter, means for moving a bight of a thread into proximity to the knotter, means to withdraw a strand of the bight, and means operating in advance of said withdrawing means to trim the thread to a uniform 45 length.

38. A winder having, in combination, means for supporting a winding couple, a detector to detect exhaustion of the thread of said couple, a brake to stop the rotation 50 of the receiving member of the couple upon exhaustion of the thread, a clamp to hold the exhausted thread, a reserve thread holder, means to unite the exhausted and reserve threads, and means to open the 55 clamp.

39. A winder having, in combination, a series of container supports, a container-brake for each container, and means arranged to travel along the series and successively release the brakes.

40. A winder having, in combination, a series of container supports, a thread-restrained brake for each container, and means arranged to travel along the series and successively release the brakes.

41. A winder having, in combination, a bobbin support, a winding device arranged to draw yarn from a bobbin on said support, and a tension-reducing roll over which the thread runs intermediate the bobbin and the winding device, said roll being driven at a greater surface speed than the speed of the thread.

42. A winder having, in combination, a container support, container-rotating means, 75 a brake device tending to move into braking relation to the container, a movably-supported member connected with said brake device and arranged to be supported by the thread being wound on the container, and 80 means simultaneously to reset said member and said brake device after actuation.

43. A winder having, in combination, a pivoted frame, a container-supporting member rotatably carried by said frame, means 85 for rotating a container carried by said member, a brake device adapted to engage said member, a spring exerting its force upon said brake device and said frame, thread-controlled means for restraining said 90 brake device, means to withdraw the brake device after actuation, and means to restrain the frame when the brake device is withdrawn.

44. A winder having, in combination, 95 means to support a winding couple, a detector to detect exhaustion of the thread of said couple, a brake to stop rotation of the receiving member of the couple, said brake being controlled by the detector, a clamp to 100 hold the thread of the couple when exhausted, a reserve thread holder, and means to unite the reserve thread and the exhausted thread.

45. A winder having, in combination, 105 means to support a winding couple, a detector to detect exhaustion of the thread of said couple, a spring-actuated brake to stop rotation of the receiving member of the couple, a spring-actuated clamp to hold the 110 thread of the couple when exhausted, said brake and clamp being restrained by the detector, a reserve thread holder, and means to unite the reserve thread and the exhausted thread.

46. A winder having, in combination, means to support a winding couple, a detector to detect exhaustion of the thread of said couple, a brake to stop rotation of the receiving member of the couple, a clamp to 120 hold the thread of the couple when exhausted, said brake and clamp being controlled by the detector, a reserve thread holder, and means to unite the reserve thread and the exhausted thread.

47. A winder having, in combination, a supporting framework; means on the framework for supporting a winding couple; means on the framework for supporting the thread of the couple when exhausted; means 125

on the framework for supporting a reserve thread; a knotter; means for moving one of said threads and a bight of the other thread into operative relation to the knotter; and 5 means acting prior to the knotter for withdrawing one strand of the bight.

48. A winder having, in combination, a reserve thread holder, means to support an exhausted thread, a knotter, a pivoted arm 10 having a clamp to receive the reserve thread and being adapted to deflect the exhausted thread into the form of a bight and draw said bight and the reserve thread into proximity to the knotter, means to withdraw one 15 strand of the bight, and means to move the remaining strand and the reserve thread into the knotter.

49. A winder having, in combination, a knotter, means for moving a bight of a 20 thread into proximity to the knotter, a device to pull away one strand of the bight, and a device to move the remaining strand into the knotter.

50. A winder having, in combination, a knotter, a member to move a bight of a 25 thread into proximity to the knotter, a shear acting in advance of said member to trim the thread to a uniform length, a device to pull away one strand of the bight, and a device to move the remaining strand into the 30 knotter.

51. A winder having, in combination, a row of container supports, a row of clamps for the ends of exhausted threads of containers located on said supports, said rows being parallel, a knotter arranged to travel between said rows, a reserve thread holder adjacent to each of said clamps, a pivoted arm traveling with the knotter, said arm 35 having a clamp to receive the reserve thread and being adapted to deflect the exhausted thread into the form of a bight and draw said bight and the reserve thread into proximity to the knotter, means to withdraw one 40 strand of the bight, and means to move the remaining strand and the reserve thread into the knotter.

52. A winder having, in combination, means to support a winding couple, a clamp 45 to hold the thread of said couple when exhausted, a reserve thread holder, a knotter, a device for moving a reserve thread and a bight of the exhausted thread into proximity to the knotter, means to withdraw one 55 strand of the bight, and means to move the remaining strand and the reserve thread into the knotter.

53. A winder having, in combination, means to support a winding couple, means 60 to guide the thread of the couple, a reserve thread holder, a knotter, and a device to take the reserve thread from the holder and draw said thread across said guiding means and to the knotter.

54. A winder having, in combination,

means to support a winding couple, means to guide the thread of the couple, means to support said thread when exhausted, a reserve thread holder, a knotter, and a device to take a reserve thread from the holder, 70 place the reserve thread on said guiding means and move the reserve thread and the exhausted thread to the knotter.

55. A winder having, in combination, a building element, means for reciprocating said element, means for detaining said element at one end of its travel, and means for operating said detaining means to release the element. 75

56. A winder having, in combination, a building element, means to move said element, a uniting mechanism arranged to travel along the winder, and means traveling with the uniting mechanism for moving the building element co-operatively with the 80 action of the uniting mechanism. 85

57. A winder having, in combination, a building element, a uniting mechanism arranged to travel along the winder, and a stationary cam-bar traveling with said mechanism and arranged to engage and raise the 90 building element. 95

58. A winder having, in combination, a building element, constantly-acting means adapted to reciprocate the building element, 95 and an auxiliary means arranged to travel along the winder for moving the building element. 100

59. A winder having, in combination, a reciprocating building element, constantly-acting means for raising the building element, 100 a carriage arranged to travel along the winder, and auxiliary means on the carriage for raising the building element.

60. A winder having, in combination, a building element, a carriage arranged to travel along the winder, a knot-tying mechanism on the carriage, an arm pivoted on the carriage and arranged to engage a thread extending over the building element and 105 carry the thread into proximity to the knot-tying mechanism, and means on the carriage for raising the building element before the lever engages said thread. 110

61. A winder having, in combination, a building element, a carriage arranged to travel along the winder, a knot-tying mechanism on the carriage, an arm pivoted on the carriage and arranged to engage a thread extending over the building element 115 and carry the thread into proximity to the knot-tying mechanism, means on the carriage for raising the building element before the lever engages said thread, and means on the carriage for moving the thread into the 120 knot-tying mechanism, the building-element-raising means being arranged to permit the building element to descend as the thread is being moved into the knot-tying mechanism. 125 130

62. A winder having, in combination, a building element, a carriage arranged to travel along the winder, a knot-tying mechanism on the carriage, an arm pivoted on the carriage and arranged to engage a thread extending over the building element and carry the thread into proximity to the knot-tying mechanism, a stationary cam on the carriage for raising the building element 5 before the lever engages said thread, and means on the carriage for moving the thread into the knot-tying mechanism, said cam being arranged to permit the building element to descend as the thread is being moved into 10 the knot-tying mechanism.
63. A winder having, in combination, container-rotating means, a container support movable to place the container in and out of contact with the rotating means, means for 15 braking the container to stop its winding rotation, means to keep the container away from the rotating means, and means to release the brake.
64. A winder having, in combination, container-rotating means, a container support movable to place the container in and out of contact with the rotating means, means to 20 brake the container to stop its winding rotation, a carriage arranged to travel past the container, means on said carriage to keep the container away from the rotating means, and means on the carriage to release the 25 brake.
65. A winder having, in combination, container-rotating means, a container support movable to place the container in and out of contact with the rotating means, means to 30 brake the container to stop its winding rotation, a carriage arranged to travel past the container, means on said carriage to keep the container away from the rotating means, and a cam on the carriage to release the 35 brake.
66. A winder having, in combination, container-rotating means, a container support movable to place the container in and out of contact with the rotating means, means to 40 brake the container, a building element, means for raising said element, means for preventing downward movement of the element, said preventing means being arranged to operate with the brake, a carriage arranged to travel past the container, means on said carriage to keep the container away 45 from the rotating means, and means on the carriage to release the brake and the movement-preventing means.
67. A winder having, in combination, container-rotating means, a container support 50 movable to place the container in and out of contact with the rotating means, means to brake the container, a building element, means for raising said element, means for preventing downward movement of the element, said preventing means being arranged to operate with the brake, a carriage arranged to travel past the container, means on said carriage to keep the container away 55 from the rotating means, and means on the carriage to release the brake and the movement-preventing means.
68. A winder having, in combination, means to support a winding couple, a roll to guide the thread of the couple, a clamp 60 to support said thread when exhausted, a reserve thread holder, a knotter, and a device to take a reserve thread from the holder, place the reserve thread on said roll, draw the reserve thread into position 65 over the clamp, and thence move the reserve thread and the exhausted thread to the knotter.
69. A winder having, container-rotating means, a pivoted container support 70 arranged to carry a container into and out of contact with the container-rotating means, means for braking the container, said braking means including a member pivoted on the axis of said container-support, the momentum of said member causing the container support to withdraw from the rotating means, and means to release the 75 braking means.
70. A winder having, in combination, a series of container supports, container-rotating means, means for braking the containers, a series of bobbin supports, means for supporting reserve threads, and a traveling thread-uniting mechanism comprising a knot-tying mechanism and a pivoted arm arranged to engage a reserve thread and a thread extending from a braked container and move them into proximity to the knot-tying mechanism. 80
71. A winder having, in combination, a container-support, container-rotating means, a bobbin support, means for uniting a thread on the container to a thread on the bobbin, means for preventing rotation of the container, means for initiating rotation of the bobbin, and means for controlling said rotation-initiating means. 85
72. A winder having, container-rotating means, a pivoted container support arranged to carry a container into and out of contact with the container-rotating means, a container-braking device, said device including a member pivoted on the axis of said container support, a spring tending to move the container support into operative position and to actuate the brake device, the momentum of said member causing the container support to withdraw from the rotating means, and means to release the braking device. 90
73. A winder having, in combination, means for supporting a winding couple, a

5 clamp to hold the thread of said couple when exhausted, a detector to detect exhaustion of said thread, means to form a loop in the thread between the detector and the clamp, and means for operating the loop-forming means.

74. A winder having, in combination, means for supporting a winding couple, a clamp to hold the thread of said couple when exhausted, a detector for detecting exhaustion of said thread, a looper located intermediate the detector and the clamp, and means for raising said looper into position for placing it on the thread of said couple.

15 75. A winder having, in combination, means for supporting a winding couple, a clamp to hold the thread of said couple when exhausted, a detector to detect exhaustion of said thread, a reserve thread holder, 20 a knotter, a device to take a reserve thread from the holder and move it, together with the exhausted thread, into proximity to the knotter, means for moving said threads into the knotter, and means to form a loop in the 25 united threads between the detector and the clamp.

76. A winder having, in combination, a reserve thread holder, means to support an exhausted thread, a knotter, a member having a clamp to receive the reserve thread and being adapted to deflect the exhausted thread into the form of a bight and move said bight and the reserve thread into proximity to the knotter, means to withdraw 30 one strand of the bight, means to move the remaining strand and the reserve thread into the knotter, and means for taking up slack in the united threads.

77. A winder having, in combination, a 40 row of devices for supporting winding couples, uniting means to operate upon the yarn connections of the members of said couples, a plurality of devices for taking up slack in the yarn connections, there being 45 one slack-take-up device for each winding couple, and means for operating said slack-take-up devices.

78. A winder having, in combination, a 50 bobbin-holder, means for supporting a receiving container, a detector to detect exhaustion of the thread being wound, a clamp to hold said thread when exhausted, said clamp being located between the detector and the receiving container, a brake 55 to stop the receiving container upon exhaustion of the thread, means to form a loop in the thread between the detector and the clamp, and means to join a reserve thread to the exhausted thread.

60 79. A winder having, in combination, means to support a winding couple, a clamp to hold the thread of said couple when exhausted, a detector to detect exhaustion of said thread, a reserve thread holder, a knot-

ter, means to move the exhausted thread and the reserve thread into the knotter, and means to produce a loop in the united threads between the clamp and the detector.

80. A winder having, in combination, means for uniting two threads, a looper, and 70 means for placing the looper on the united threads.

81. A winder having, in combination, means for uniting two threads, and means for forming a loop in said threads to take 75 up slack therein.

82. A winder having, in combination, means for uniting two threads, a looper, means for placing said looper in position upon the united threads, and means for controlling gravitating movement of 80 said looper.

83. A winder having, in combination, means for uniting two threads, a looper, means for placing said looper in position to 85 descend upon the united threads, and cam means for controlling the gravitating movement of said looper, and for dividing said gravitating movement into two stages, during one of which stages the looper forms a 90 loop in the united threads to take up slack therein, and during the other of which stages the looper lengthens the loop.

84. A winder having, in combination, a looper supported for vertical movement, 95 mechanism arranged for horizontal travel, said mechanism comprising an endless chain supported in an inclined plane and carrying means to engage the looper, and means for moving said chain in the travel of said 100 mechanism to elevate the looper.

85. A winder having, in combination, means for supporting a winding couple, means for uniting the threads of the two members of the couple, and gravity-actuated 105 means for taking up slack in the united threads.

86. A winder having, in combination, a supporting framework, a detector element pivoted on said framework and arranged to 110 bear against a thread, means to swing the detector element away from the thread, a movable stop on said framework to limit the return movement of the detector element, and means for withdrawing said stop from 115 engagement with the detector element.

87. A winder having, in combination, a supporting framework, a detector element pivoted on said framework and arranged to bear against a thread, traveling means to 120 swing the detector element away from the thread, means on said framework to limit the return movement of the detector element, and traveling means for withdrawing said 125 limiting means from engagement with the detector element.

88. A winder having, in combination, a pivoted detector element arranged to bear

- against a thread, means to swing the detector element away from the thread, a spring-actuated stop to limit the return movement of the detector element, and a 5 traveling cam for withdrawing said stop from engagement with the detector element.
89. A winder having, in combination, a pivoted detector element, means including a spring for causing said element to move 10 against a thread, means to swing the detector element in the opposite direction, a spring-actuated stop to limit the return movement of the detector element, and means for withdrawing said stop from engagement with the detector element.
90. A winder having, in combination, a knotter, an arm for moving a thread into proximity to the knotter, and thread-trimming means arranged to operate upon the 15 thread prior to the action of the arm thereon, to trim said thread to a uniform length.
91. A winder having, in combination, means to support a winding couple, a clamp to hold the thread of said couple when exhausted, a detector to detect exhaustion of said thread, a reserve thread holder, a knotter, a device having a clamp to receive the reserve thread and being adapted to deflect the exhausted thread into the form of a 20 bight and draw said bight and the reserve thread into proximity to the knotter, means to withdraw one strand of the bight, means to move the remaining strand and the reserve thread into the knotter, and means to 25 produce a loop in the united threads between the clamp and the detector.
92. A winder having, in combination, means for supporting a winding couple, a knotter, a swinging arm, a thread clamp on 30 said arm, means for swinging said arm to carry a thread of the couple into proximity to the knotter, and means for opening and closing the clamp.
93. A winder having, in combination, a 35 supporting framework, means on the framework for supporting winding couples, reserve thread holders on the framework, a knotter arranged to travel along the framework, means traveling with the knotter for moving a reserve thread and an exhausted thread to the knotter, means on the framework for taking up slack in the united threads, and means traveling with the knotter for operating the slack-take-up means.
- 55 94. A winder having, in combination, a reserve-thread holder, a knot-tying mechanism, and a pivoted arm arranged to swing from the reserve-thread holder to and past the knot-tying mechanism.
- 60 95. A winder having, in combination, a reserve-thread holder, a knot-tying mechanism, a pivoted arm arranged to swing from the reserve thread holder to and past the knot-tying mechanism, and means for moving into the knot-tying mechanism a 65 reserve thread taken by said arm.
96. A winder having, in combination, a knot-tying mechanism, a reserve thread holder means for moving the reserve thread and a bight of another thread into proximity to the knot-tying mechanism, and means for withdrawing one strand of the bight. 70
97. A winder having, in combination, a knot-tying mechanism, a reserve thread holder means for moving the reserve thread 75 and a bight of another thread into proximity to the knot-tying mechanism, a swinging hook arranged to engage said bight, and an element over which said hook is arranged to pull one strand of said bight. 80
98. A winder having, in combination, a movable container support, means for moving said support into winding position, an arm attached to said support, and means arranged to travel along the winder and adapted to engage said arm for holding the support against such movement. 85
99. A winder having, in combination, a movable container support, a container brake, a looper arranged to engage the 90 thread extending from the container, means for releasing the brake, a second brake, and means for moving the support to place the container in operative relation to the second brake before the looper engages the thread. 95
100. A winder having, in combination, a movable container support, a spring for moving said support into winding position, an arm attached to said support, and means arranged to travel along the winder and 100 engage said arm to hold the support against such movement.
101. A winder having, in combination, a movable container support, a spring for moving said support into winding position, 105 an arm attached to said support, and means arranged to travel along the winder and engage said arm to move the support in the opposite direction.
102. A winder having, in combination, a movable support, means for moving said support in one direction, an arm attached to said support, a container brake, and means arranged to travel along the winder and engage said arm to move the container into 110 operative relation to the brake.
103. A winder having, in combination, a movable container support, a container brake, a looper arranged to engage the thread extending from the container, a carriage arranged to travel along the winder, 115 means on the carriage for releasing the brake, a second brake, means on the carriage for placing the looper in engagement with the thread, and means on the carriage 120 for moving the support to place the container in operative relation to the second brake before the looper engages the thread. 125

104. A winder having, in combination, a movable container support, means for moving said support into winding position, an arm attached to said support, a carriage 5 arranged to travel along the winder, and a cam on the carriage arranged to engage said arm for holding the support against such movement.

105. A winder having, in combination, a 10 supporting framework, a container support, pivoted on said framework, means on said framework for moving said support into winding position, an arm attached to said support, a carriage arranged to travel along 15 the winder, and a cam on the carriage arranged to engage said arm to move the support in the opposite direction.

106. A winder having, in combination, a 20 container support, means for moving said support in one direction, an arm attached to said support, a carriage arranged to travel along the winder, a container brake, and a cam on the carriage arranged to engage said arm to move the container into 25 operative relation to the brake.

107. The combination of an elongated supporting frame; an endless track in said frame, said track having opposite straight portions and curved ends connecting said 30 straight portions; pairs of bobbin-holders supported along the outer side of the straight track-portions; means for holding, adjacent the straight track-portions, the end of the thread of one of the bobbins in each 35 pair of holders; means for unwinding the other bobbin in each pair of holders toward the inner side of the straight track-portions, whereby the running threads pass across the straight track-portions; a knot-tying mech- 40 nism arranged to travel upon said track; and means coöperating with said knot-tying mechanism for placing an exhausted thread and the thread-end of the companion bobbin in coöperative relation with said 45 knot-tying mechanism.

108. A winder having, in combination, means for supporting a series of winding couples, a series of reserve thread holders, a knotter arranged to travel along said series, means traveling with the knotter for moving a reserve thread and an exhausted 50 thread to the knotter, a series of devices for taking up slack in the united threads, and means traveling with the knotter for successively operating the slack-take-up devices.

109. A winder having, in combination, a series of container supports, a series of clamps for the ends of exhausted threads of containers located on said supports, a series 60 of reserve thread holders, a knotter arranged to travel longitudinally of said series, means for moving a reserve thread and an exhausted thread to the knotter, and means for taking up slack in the united threads.

110. A winder having, in combination, a 65 supporting framework, a row of container supports on the framework, a row of clamps on the framework for the ends of exhausted threads of containers located on said supports, said rows being parallel, a knotter ar- 70 ranged to travel longitudinally of said rows, a reserve thread holder adjacent to each of said clamps, means traveling with the knotter for moving a reserve thread and an ex- 75 hausted thread to the knotter, means on the framework for taking up slack in the united threads, and means traveling with the knotter for operating the slack-take-up means.

111. A winder having, in combination, a 80 row of container supports, a row of clamps for the ends of the exhausted threads of containers located on said supports, said rows being parallel, a reserve thread holder adjacent to each clamp, a knotter arranged to travel longitudinally of said rows, a device 85 for moving a reserve thread and the bight of an exhausted thread into proximity to the knotter, means to withdraw a strand of the bight, means for moving the remaining strand and the reserve thread into the knot- 90 ter, and means for taking up slack in the united threads.

112. A winder having, in combination, means for supporting a series of winding couples, a series of clamps each adapted to 95 hold the thread of a winding couple when exhausted, and means for opening the clamps.

113. A winder having, in combination, means for winding a series of threads, a series of clamps each adapted to hold one of 100 said threads when exhausted, and means arranged to travel along said series for successively opening the clamps.

114. A winder having, in combination, means for supporting a series of winding 105 couples, a series of brakes each adapted to stop the rotation of the receiving member of a couple upon exhaustion of its thread, a series of clamps each adapted to hold the exhausted thread of a couple, and means to release the brakes and open the clamps. 110

115. A winder having, in combination, means for supporting a series of winding couples, a series of brakes each adapted to stop the rotation of the receiving member of 115 a couple upon exhaustion of its thread, a series of clamps each adapted to hold the exhausted thread of a couple, and means arranged to travel along said series for releasing the brakes and opening the clamps.

116. A winder having, in combination, means to support a winding couple, a detector to detect exhaustion of the thread of said couple, a spring-actuated brake to stop rotation of the receiving member of the couple, said brake being restrained by the detector, a clamp to hold the thread of the couple when exhausted, a reserve thread holder, 120 125

means to unite the reserve thread and the exhausted thread, and means to reset the detector and release the brake.

117. A winder having, in combination, 5 means to support a series of winding couples, a series of detectors to detect exhaustion of the threads of the couples, a series of brakes to stop rotation of the receiving members of the couples, and means arranged 10 to travel along said series for resetting the detectors and releasing the brakes.

118. A winder having, in combination, means to support a winding couple, a detector to detect exhaustion of the thread of 15 said couple, a spring-actuated brake to stop rotation of the receiving member of the couple, a spring-actuated clamp to hold the thread of the couple when exhausted, said brake and clamp being restrained by the 20 detector, a reserve thread holder, means to unite the reserve thread and the exhausted thread, and means to reset the detector and release the brake and the clamp.

119. A winder having, in combination, 25 means to support a series of winding couples, a series of detectors to detect exhaustion of the threads of the couples, a series of brakes to stop rotation of the receiving members of the couples, a series of clamps to 30 hold the threads of the couples when exhausted, and means arranged to travel along said series for resetting the detectors and releasing the brakes and the clamps.

120. A winder having, in combination, 35 a series of detectors, a thread clamp associated with each detector and normally held open by its detector, means tending to close each clamp, and a device arranged to travel along the series to open the clamps.

40 121. A winder having, in combination, means for supporting a winding couple, a device for traversing the yarn, uniting means to operate upon the yarn connection of the couple, and means for preventing operation 45 of the traversing device during operation of the uniting means.

122. A winder having, in combination, 50 means for supporting a winding couple, a device for traversing the yarn, a reserve thread holder, means for uniting the reserve thread to the thread of the couple, and means for preventing operation of the traversing device during operation of the uniting means.

55 123. A winder having, in combination, means for supporting a winding couple, a device for traversing the yarn, a reserve thread holder, means for uniting the reserve thread to the thread of the couple, and 60 means for keeping the traversing device at one end of its traverse during operation of the uniting means.

124. A winder having, in combination, means for supporting a winding couple, a

yarn-traversing device, a knotter, means for 65 placing the thread of the couple in the knotter, and means for operating the yarn-traversing device to allow such movement of the thread.

125. A winder having, in combination, 70 means for supporting a winding couple, a yarn-traversing device, a reserve thread holder, a knotter, a device for moving the reserve thread and the exhausted thread of the couple into proximity to the knotter, a 75 device for moving said threads into the knotter, and means for operating the yarn-traversing device to allow movement of the exhausted thread as the threads are moved into the knotter. 80

126. In a winder, means for supporting a winding couple, means for uniting the threads of the two members of the couple, means for taking up slack in the united threads, and means to prevent rotation of 85 the receiving member of the couple during the operation of the slack-take-up means.

127. In a winder, the combination of means for uniting the threads of two yarn masses, means for forming a loop in the 90 united threads to take up slack therein, and means to prevent rotation of one of said yarn masses during the operation of the loop-forming means.

128. A winder having, in combination, 95 a container support, a brake for stopping the rotation of the container upon exhaustion of its thread, means for releasing the brake, means for operating upon the thread, a second brake for the container, and means for 100 causing application of the second brake.

129. A winder having, in combination, means to support a winding couple, a reserve thread holder, a knotter, a thread-support near the knotter, a pivoted arm arranged to carry a reserve thread and a bight of the thread of the couple to and past the knotter and lay said threads across said thread support, means to withdraw one strand of the bight, and means to move the 110 remaining strand and the reserve thread into the knotter. 105

130. A winder having, in combination, 115 means to support a winding couple, a reserve thread holder, a knotter, a thread-support near the knotter, a pivoted arm arranged to carry a reserve thread and the thread of the couple to and past the knotter and lay said threads across said thread support, and means to move the threads into 120 the knotter.

131. A winder having, in combination, means to support a winding couple; means to guide the thread of the couple; a reserve thread holder; a knotter; and a device to 125 take a reserve thread from the holder, place the reserve thread on said guiding means, and move the reserve thread to the knotter.

132. A winder having, in combination, means for supporting a winding couple, means engaging the thread of the couple to set the supplying member in rotation, and 5 means acting subsequently to said thread-engaging means to revolve the receiving member of the couple to draw thread from the supplying member.

HOWARD D. COLMAN.
